UNITED STATES PATENT OFFICE.

WALTER F. KOKEN, OF ST. LOUIS, MISSOURI.

DESIGN FOR A BARBER'S CHAIR.

47,236.

Specification for Design.

Patented Apr. 13, 1915.

Application filed January 18, 1915. Serial No. 2,986. Term of patent 14 years.

To all whom it may concern:

Be it known that I, WALTER F. KOKEN, a citizen of the United States, residing at St. Louis, Missouri, have invented a certain new, original, and ornamental Design for a Barber's Chair, of which the following is a specification, reference being had to the accompanying drawing, forming part thereof.

The figure of the drawing is a perspective view of my new design for a barber's chair.

The design consists in a barber's chair in which the back, the seat, the apron and footrest are substantially shield-shaped in outline.

I claim:

The ornamental design for a barber's chair, as shown.

WALTER F. KOKEN.
